UNITED STATES PATENT OFFICE.

SAMUEL SÜSZ, JR., AND EDMUND SÜSZ, OF BUDAPEST, HUNGARY.

SIPHON HEAD WITH BAYONET JOINT.

Application filed January 25, 1927, Serial No. 163,464, and in Hungary February 3, 1926.

This invention relates to a siphon head with bayonet joint, wherein one member of the closure consists of an extension of the head extending into the neck part of the bottle, with projections, while the other member of the closure is formed by an inwardly projecting flange on the neck of the vessel, with notches for the introduction of the extension projections.

10 The accompanying drawings show one constructional example of the invention. In these drawings,

Figure 1 shows the siphon head in elevation,

15 Figure 2 a part of the bottle neck in sectional elevation,

Figure 3 the siphon head mounted on the bottle neck, partly in section, and

20 Figure 4 a horizontal section on the line A—B in Figure 3.

At the lower end of the siphon head *b* of known form, equipped with a plunger valve *a*, is constructed a cylindrical extension *d* which has the same diameter as the mouth *i* 25 of the bottle neck *c*, and which has at the lower end two diametrically opposite projections *e*.

On the upper, inwardly projecting flange *f* of the bottle neck are provided two notches *g*, corresponding to the projections *e*.

30 On to the extension *d* is pulled an ordinary packing ring *h*.

During the fastening of the siphon head the projections *e* are simply placed upon the notches *g* and the extension *d* is introduced through the mouth *i* into the neck space, 35 whereupon the siphon head is twisted, with simultaneous compression of the packing ring *h*, so that the projections press against the flange *f*, as shown in dotted lines in Figure 4. In this manner the siphon head is held fast 40 to the bottle neck in the manner of a bayonet joint.

When releasing the connection the head is simply rotated back until the projections coincide with the notches *g*, so that the head can 45 be lifted out.

Both the mounting and the removal of the siphon head are effected by a single manual operation.

What we claim is:—

In combination, a siphon head, an extension on said head, lateral projections on said extension, a neck part having an inwardly projecting flange formed internally thereof adapted to receive the extension, said flange 55 being formed with notches through which the projections on the extension may be introduced or removed.

In testimony whereof we have signed our names to this specification.

SAMUEL SÜSZ, JUNIOR.

EDMUND SÜSZ.
